MACHINE FOR TREATING SHEET MATERIALS

David Edgar, Lynn, Mass., assignor to United Shoe Machinery Corporation, Flemington, N. J., a corporation of New Jersey

Application April 29, 1943, Serial 485,001

27 Claims. (Cl. 69—41)

This invention relates to machines for treating sheet materials and is herein illustrated as embodied in a machine for performing putting-out operations on hides and skins. It should be understood that the term "hide" is used generically in this specification and in the appended claims to include not only hides, but also skins and other materials analogous thereto. The operation performed obviously need not be limited to a putting-out operation but may consist in some other form of treatment of sheet materials. The machine illustrated shows blades for a putting-out operation. However, other forms of tools for treating sheet materials could well be substituted and the number of tools as well as the type of tool carrying members could be changed without departing from the spirit and scope of this invention.

It is an object of the invention to provide a machine in which sheet material to be treated may be spread out in a single plane and passed into and through a treating zone in which zone progressive overlapping areas of the material may be treated by suitably arranged tools against which the material may be pressed, the pressure being applied while a given piece of material has entered the treating zone and being released when such piece of sheet material has been adequately treated, after which such piece of material may be discharged.

Still a further object is a provision of such a machine in which the presence of each work piece of sheet material entering the machine will initiate the application of pressure of such work piece against the treating tools and the completion of adequate treatment of that work piece will terminate such application of pressure permitting free discharge of such work piece preliminary to the reception of the next piece to be treated.

For the purposes in view and in accordance with further features of the invention the illustrated machine is provided with a table over which the sheet material is conveyed in passing through the treating zone and means for lifting the table to press a piece of sheet material against the tools, the said means also serving as a means for lowering the table and relieving the pressure after that piece of material has been treated. Preferably, but not necessarily, fluid pressure means is provided for lifting and lowering the table. Further novelty is to be recognized in an arrangement of parts in which detector or feeler devices are actuated by the entrance of a work piece into the treating zone to lift the table and by the departure of the work piece from the treating zone to lower the table.

Another object of the present invention is to provide a machine in which sheet material, after being laid out on a single plane or continuous

surface by an operator, and while so laid out, is passed by suitable conveyor means through a treating zone wherein suitable tool sets are provided for acting outwardly in at least four diverging directions or paths on the sheet material from a central area in the treating zone, after which the material is discharged from that zone. A feature of the invention consists in providing an arrangement of sets of individual tools which may be said to be mounted for diverging paths of movement at each side of the center line of the single plane or continuous surface of the sheet material support. Such sets may be described as being in X formation. They thereby conform generally with the flanks of sheet material such as hides or skins. In accordance with a further feature, the diverging sets of tools in the X formation are made adjustable with relation to each other to suit given conditions such as the type of the material to be treated, rate of passage of the material through the machine and the nature of the treatment. In accordance with another feature of the invention there is provided an arrangement of tool sets in addition to those of the X formation and mounted in the same plane to minimize the possibility of any portion of the sheet material escaping treatment.

In accordance with still another feature of the invention novel means is provided for holding sheet material in position on and in relation to a conveyor belt during treatment of the material against any undue shifting under the action of the treating tools on the material.

The above and other features of the invention, including novel details of construction and combinations of parts will now be more particularly described in connection with the accompanying drawings and pointed out in the claims.

In the drawings,

Fig. 1 is a view in side elevation of a machine in which the invention is embodied, showing the main putting-out tool members turned to permit easy and clear illustration, and with the work support or table in lowered or inoperative position;

Fig. 2 is an elevational view of the left end of the machine shown in Fig. 1, with the work support or table in operative position and including the forward end of the conveyor belt arrangement upon which the sheet material is introduced by the operator for treatment by the machine;

Fig. 3 is a plan view of the machine shown in Fig. 1, some of the parts being broken away to show more clearly the construction thereof;

Fig. 4 is an enlarged plan view taken along the line IV—IV of Fig. 1, two supporting beams being merely blocked in for purposes of clarity;

Fig. 5 is an enlarged plan view of the tool

carrying member shown in the upper left-hand corner of Fig. 3;

Fig. 6 is an enlarged elevational view of any one of the four long diverging tool members shown in Fig. 3, the supporting frame portions being in section;

Fig. 7 is a sectional view along the line VII—VII of Fig. 6;

Fig. 8 is a sectional view along the line VIII—VIII of Fig. 6;

Fig. 9 is an enlarged plan view of some of the structural details including the switch members for controlling the operation of the work table and also showing one of the two short tool members, this member being also shown in the left half of Fig. 3. In Fig. 9 the main frame members of the machine are not shown for purposes of clarity; and

Fig. 10 is an elevation of the structure shown in Fig. 9 and taken along the line X—X.

In the illustrated machine which is designed for treating sheet materials, and particularly for putting-out operations on hides, main supporting columns 10 and 12 and horizontal members 14 and 204 together with longitudinal parallel upper channel beams 16 are shown (Fig. 1). The main frame members 10, 12, 14 and 204 are duplicated on the other side of the machine and together with suitable transverse stiffening beams such as 18 and 20 form a rigid and sturdy frame. Columns 22 (Fig. 1) are mounted upon the members 14 on each side of the machine and at their tops support back-to-back spaced channel bars 24 at their outer ends. These back-to-back channel bars are suitably mounted at their other ends to the main frame of the machine and are angularly placed as shown in Fig. 3. Each set of back-to-back channel bars 24 serves as a support for the outer end of a tool member or tool carrier designated generally by character 26, 28, 30 or 32 (Fig. 3). The space 34 between the backs of each set of channel bars 24 serves as a slot by means of which the outer end of each tool carrying member 26, 28, 30 or 32 may be adjusted in position to vary the angular position of that tool carrying member in the X formation and thereby suit various sizes of hides to be treated or to suit various conditions. Bolts 36 (Figs. 3 and 8), for each of such sets, are utilized for this purpose. They pass through the slots 34 (Fig. 3) between the channel bars 24 and also through slots 37 in the central portions of plates 38 (Figs. 5 and 8). Rods 40 depend from the plate 38 and adjustably support brackets 42 and 43 by means of nuts 44 and 46 (Fig. 8). The bracket 42 carries bearing 48 and bracket 43 carries bearing 50 in which bearings a shaft 52 is journaled. Upon the shaft 52 is mounted a sprocket wheel 54 having a hub 56. On the opposite ends of the brackets 42 and 43 are suitable flanges 58 (Figs. 5 and 6) to which a plate 60 is secured by means of bolts 62 and 64. Slots 66 and 68 are provided in the plate 60 by which adjustment may be made to compensate for wear in a chain to be described. The other or inner ends of the long tool carrying members 26, 28, 30 and 32 are supported from transverse plates 70 by means of bolts 72, plates 74, dependent rods 76 and brackets 78 and 80 (Fig. 7). Slots 71 (Fig. 4) in plates 70 and slots 73 in plates 74 permit further adjustment of the long tool members 26, 28, 30 and 32 relative to the machine frame. The brackets 78 and 80 are vertically adjustable by means of bolts in the same manner as are the brackets 42 and 43. Each plate 60 extends from

a bracket 42 to and beyond a set of brackets 78 and 80. The upper edge, the lower edge, and the innermost end face 82 of each plate 60 is adapted to serve as a narrow bearing surface for the rollers of a chain 86. Angle bars 88 (Fig. 8) are mounted on the plate 60 and suitably spaced therefrom by spacers 90 and bolts 91. The angle bars 88 serve as guiding means for the chain 86 by engagement with U-shaped members 92 secured to the chain. The U-shaped members 92 form part of each chain and to them are fastened and supported the putting-out tools or blades 94. The blades 94 are herein shown as mounted on every other link of the chain. However, the blades or tools may be mounted nearer or farther apart as occasion demands. The tools 94, of the illustrated machine, are in the form of angle bars, each angle bar having both its edge faces beveled to form a dull edge. When one edge of a bar is unduly worn, that bar can be reversed in position to present the other edge to the material being treated. Other forms of tools may obviously be substituted and be mounted differently, as hereinbefore stated. In addition to the above-described sets of working tools which diverge horizontally to constitute what may be described as an X formation, two additional but shorter sets of tools are located in the same plane as those in the X formation and in line with the central portion of the machine, as shown in Fig. 3 as well as in Fig. 1. These two additional sets are identical in structure but opposed in position. Each short set is provided with two plates 96 and 98 extending from the under side of one machine frame member 16 to the under side of the other machine frame member 16 (Fig. 3). The construction and support of these sets is clearly shown in Figs. 9 and 10. A horizontal plate 99 is centrally bolted to plate 96 and a second horizontal plate 101 is similarly bolted to plate 98. Two rods 100 depend from the plate 99 and by means of brackets 104 support one end of a vertical plate 106. The brackets 104 are vertically adjustable on the rods 100, as clearly shown in Fig. 10. This end of the plate 105 has its narrow end and bottom edge utilized as the means on which the rollers of a chain 108 bear. Two rods 102 depend from the plate 101 and support vertically adjustable brackets 110 and 111. The brackets 110 and 111 support two bearings 114 and 112 in which a shaft 116 is journaled. Sprocket 118 with hub 119 is mounted on the shaft 116. Plate 106 is secured to the brackets 110 and 111 by bolts 120 which extend through lengthwise slots in the plate so as to permit horizontal adjustment of the plate and the chain 108. The chain 108 carries putting-out tools 124 which are similar to the putting-out tools 94. Here again, other types of tools, such as brushes, for example, may be used, depending upon the treatment desired for the sheet material.

In each of the six sets of tools an endless roller chain 86 or 108 is provided which passes over a driving sprocket 54 or 118 and around a suitably formed and fixed plate 60 or 106 whereby the lower run of the chain is adapted to be in running engagement with the lower edge of said plate. It is to be understood that six sets of tools are not necessary and that the four longer sets (in the X formation) may well be sufficient for some types of work. The two shorter sets are added, in the preferred arrangement shown, to insure that no part of sheet material passing through the machine will es-

cape adequate treatment, as will further appear. The inner ends of the tool sets in the X formation may be located in various positions, by modifications not shown in the drawings, to minimize the possibility that some portion of the sheet material would not be treated. With this end in mind, the tool sets may be arranged in such a way that tool set 30 would extend across the longitudinal center line of a belt 200 carrying the sheet material and the tool set 32 would be located at a position farther along the belt to clear the tool set 30. Sets 26 and 28 may be also located in such a way that one or both of them extend across the center line of the belt 200 and yet do not interfere with each other. Such an arrangement is possible with or without a change in angularities of the tool sets with respect to one another. In the specific embodiment shown in the drawings (Figs. 3 and 4), the individual blades or tools 94 of set 30 are operatively arranged to alternate with the individual tools 94 of the set 32 to preclude non-treatment of any work piece area. The tools of sets 26 and 28 are arranged similarly.

Motive power for the six sets of tools shown in the drawings is derived from a motor 126 mounted upon the main frame members 16. The motor shaft 128 drives a sprocket 130 and by means of chains 140 and 142, together with sprockets 132, 134 mounted on the shaft 150 and sprocket 136 on shaft 144, rotate the shaft 144. Arrows in Fig. 1 show the directions of rotation. The latter shaft, in turn, drives shafts 146 and 148 by the use of universal joints, as shown in Fig. 3, and they, in turn, drive the sprocket shaft 52 of each of the tool carrying members 30 and 32 by the use of additional universal joints. The sprockets 132 and 134 are mounted on shaft 150 which is suitably mounted in brackets 152 and 154 on the longitudinal frame members 16 (Figs. 1 and 3). On the shaft 150 and keyed thereto is a gear 156 (Fig. 3) which is in mesh with a gear 158 fast to a shaft 160 which is mounted in brackets adjacent and similar to the brackets 152 and 154 for supporting the shaft 150. Shaft 160 has mounted thereon a sprocket 162 which, through chain 164 and sprocket 166, drives a shaft 168. Shaft 168 is suitably mounted in bearings on the frame of the machine and drives the tool carrying chains of members 26 and 28 in the same manner as is done by shaft 144 with respect to the members 30 and 32. The above description pertains solely to the driving of those sets of tools in the X formation and the use of the universal joints permits adjustment of the angles of diversion of such sets. Shafts 146 and 148 and the opposite corresponding shafts are all telescopically arranged.

The short set of tools, shown in Figs. 9 and 10 and in the left-hand side of Fig. 1, is driven from the shaft 144 by sprocket 138 and chain 172, sprocket 174 and sprocket 118, the latter two sprockets being keyed to shaft 116. The other short chain of tools is similarly driven but from the shaft 168, sprocket 170, chain 176, sprockets 178 and 180. On top of the main machine frame (Figs. 1 and 3) are mounted two brackets 182 in which is journaled a shaft 184. A sprocket 186 on the motor shaft 128 drives the shaft 184 by means of chain 188 and sprocket 190. At the side of the machine, sprocket 192 is keyed to the shaft 184 and drives an endless chain 196 which passes over the idling sprockets 194 and 198 suitably journaled on the machine frame (Fig. 1). The chain 196 serves to drive a fourth sprocket 75

(not shown) by means of which the conveyor belt 200 (Fig. 2) is driven at a uniform and proper speed through the machine.

5 A flat table 202 (Figs. 1 and 2) is mounted within the columns 22 for vertical up-and-down movement. A plate 204 is placed on both sides of the machine to serve as a stiffening member for the machine frame and brackets 205 mounted on the plate 204 lend rigidity to the standards 22 to which they are affixed. The table 202 is mounted, upon four brackets 210, for vertical movement within the side plates 204. The brackets 210 rest upon the arms 212 of bell cranks 214. The bell cranks are keyed to the ends of shafts 216 suitably journaled on the frame members 14. The depending arms of the bell cranks 214 are pivoted at their lower ends to a bar or bars 218. It is to be understood that only two bell cranks (one at each end of the table 202) and one bar 218 need be used. At one end of the bar or bars 218 is a fluid-operated mechanism 220 (Fig. 2) which is arranged to oscillate the bell cranks 214 and thus to raise and lower the table 202 into and out of operative relationship with the blades 94 and 124.

10 At the forward end of the machine (Fig. 2) is mounted an extension 222 of the table 202. A similar extension 223 is located at the other end of the machine and is partially shown in Fig. 1. Both extensions are mounted for vertical movement with the table 202. The stiffening members or side plates 204 extend from the forward end of the machine (Fig. 2) and are supported at their ends on standards 206. The latter structure serves as a support for an idler pulley structure designated generally as 208. The broad work carrying belt 200 passes upwardly over a pulley 210 and thence into contact with the top surface of table 202 and its extensions 25 222 and 223, thereby passing beneath the putting-out tools 94 and 124 and out the discharge or rear end of the machine. The belt 200, being endless, will flex about a driven pulley (not shown) at the rear and exterior to the machine and pass back through the machine over idler rollers 224 mounted on the machine frame in suitable brackets 226 (Fig. 1). The stretch of the belt 200 is adequate to allow the vertical motion of the table 202 without using spring loading means on the belt. However, conventional means for maintaining a uniform tension in the belt 200 may be used if desired. The belt may be made of rubber or other suitable material. Wiper bars 225 (the ends only are shown as they are merely round bars in contact with rollers 224) may be used to aid in keeping the belt clean.

30 Extending transversely of and located substantially midway between the ends of the table 202 is a holding roll 230 which is journaled and vertically movable in brackets 232 bolted to the sides of the table. A slight clearance (less than the thickness of work to be treated) is left between the bottom of the roll 230 and the upper surface of the conveyor belt 200 to permit passage of the sheet material therethrough. The roll 230 may be rubber covered if desired and it may be held down in its lowermost position in the brackets 232 by its own weight or it may be yieldingly held down by spring means.

35 The mechanism for controlling the operation of the fluid-operated means for raising and lowering the work table 202 is illustrated particularly in Figs. 1, 2, 3, 9 and 10. The forward extension 222 of the table 202 is provided with side

members 300 which serve to support transversely extending angle bars 302 (Fig. 3). The bars 302, in turn, support two members 304 (Figs. 9 and 10) in positions above the table 202 and in fixed relation thereto. Vertical guide brackets 306 and 308 are mounted as shown and support switch rods 310 for endwise movement. Brackets 308 also support switches 312 which are adapted to be actuated by adjustable stops 314 on the rods 310. Pivots connected to the rods 310 at 316 are extension rods 318. The opposite end of each extension rod 318 is bent to form a pivoted connection with the upper end of one arm of a bell crank 320. The other arm of each bell crank 320 has pivotally connected thereto a wheel 322. Each bell crank is pivotally connected at 324 (Fig. 10) to an arm 326, the arms 326 being pivoted by means of bolts 328 to the members 304. Adjustment screws 330 are provided whereby the angular positions of the arms 326 may be regulated to give the minimum clearance desired between the wheels 322 and the conveyor belt 200. Brackets 232 (Fig. 1) support the roll 230 for vertical movement in guideways shown as already described. At the sides of each bracket 232 is pivoted at 332 a bell-crank lever 334. The upper bent-over end 336 of each lever 334 extends over an upstanding pin 338 mounted on each journal block of roll 230. The other end 340 of each lever 334 extends over and controls a switch 342. A coil spring 344 positioned at each switch 342 is under compression and serves to keep the lever end 336 in contact with pins 338 at all times. A source of power such as switch box 346 (Fig. 2) is provided by which a solenoid 348 is operated through suitable electrical wiring, indicated generally by the numeral 350. This wiring is not fully shown but is indicated in part. The solenoid 348 operates the valve mechanism 352 which controls the passage of fluid from a source of pressure 354 to cylinder and piston mechanism 220 for the reciprocation of bar or bars 218 and the lifting or lowering of the following elements as a unit: the table 202, the table extensions 222 and 223, the switches 312 and 342, and the levers and other operating mechanisms for said switches. Each switch 312 is connected into the circuit in series with the solenoid 348 and with a switch 342. The lifting of one of the wheels 322 and one end of the roll 230 away from the table 202 serves to close the switches and to operate the solenoid. The solenoid, thus operated, serves to shift the slide valve in mechanism 352 to the right as viewed in Fig. 2. The arrangement is such that such shift will admit fluid pressure from the source of fluid pressure 354 into the left-hand end of the cylinder 220 and thereby lift the table 202 and its associated elements by means of the bar 218 and the bell cranks 214. Lowering of a wheel 322 and/or one end of the roll 230 will interrupt the current passing through the solenoid, in which case spring 356 will shift the valve of mechanism 352 to the left as viewed in Fig. 2. This will establish a differential in pressure within the mechanism 220 to bring about a lowering of the table 202 with its appurtenances. As stated before, means other than that shown could be used to bring about the lifting and lowering of the table 202 and its extensions 222 and 223.

In the operation of the machine, motor 126 causes the belt 200 and the six sets of tools to run continuously as shown by the arrows in Fig. 1. A piece of sheet material, such as a hide 356, is placed upon the conveyor belt 200, as said belt

is viewed in Fig. 2, and the hide is carried thereby at a uniform rate over the table 202 and its extensions 222 and 223 in their lowered or inoperative position. When the leading edge of the hide passes beneath the wheels 322, bell cranks 320 are turned counterclockwise about pivots 324, shifting one or both rods 310 to the left (Fig. 10) and closing the switch or switches 312. Nothing happens at this stage, however, as switches 342 are open and the table 202 stays down. In the meantime, motor 126 maintains all the tool sets in motion, the lower runs of which are passing outwardly from the center of the machine. As the hide passes under the roll 230, pins 338 lift the lever ends 336 against the action of springs 344 and cause the closure of switches 342. Closure of one or both sets of switches (a set consisting of a switch 312 and a switch 342) establishes a current through the solenoid 348 and brings about the lifting of the table by fluid pressure to cause the hide to come in contact with three sets of tools, as will be readily understood. Wheels 322 are placed as close to the roll 230 as is practicable in order that as short a hide as one may desire to treat can be handled. The switch arrangement permits an interval to elapse between the time of introduction of the hide and the time for lifting of the table 202 and also causes the table to drop at the proper time. Roll 230 serves to retain the hide in position on the conveyor belt 200 against the tendency of any set or sets of tools to pull the hide excessively or unduly. Such retention is essential to prevent a piling-up of the hide and to assure a smooth passage of the hide through the machine. As long as wheels 322 and roll 230 are held up by the hide, the table 202 will remain in its hide treating or operative position. After the leading edge of the hide has passed roll 230, tool sets 26 and 28 begin to take hold and treat the hide and their operation is soon supplemented by the last short tool set. The hide continues its travel beneath the tools with the result that the entire hide area is subjected to the action of the tools. Each set of tools is so operated as to act from a central portion of the hide outwardly. The short chains or sets of tools may be omitted but their use is preferred to insure that no portion of the hide misses treatment and they also tend to maintain the hide in tension along the backbone line when the hide is introduced in that position. The longer sets of tools serve to put out the hide along the general lines or directions of the flanks, which is the most approved procedure in the manufacture of leather. It can be easily seen that with such structure the largest of hides can be treated. Side leather, for example, measures up to twelve feet, and over, in length and can be treated in this machine. When the trailing edge of the hide passes from beneath the wheels 322, switches 312 are opened, the circuit is broken and the table is lowered by fluid pressure as spring 356 operates the valve mechanism 352. Lowering of the table terminates the operation of the blades on the hide. By this time the next hide placed on the conveyor belt 200 a short distance from the first hide will have almost reached the wheels 322 and after it has passed beneath the wheels 322 and the roll 230 the table 202 is again raised for treatment of that piece of work. With a speed of 20 feet per minute of the conveyor belt 200 the machine will produce 80 sides of leather (with an average over-all measurement of eleven feet) per hour. This allows the operator suffi-

cient time to place the work pieces on the belt. With a conveyor speed of 20 feet per minute the following adjustment and setting of the machine is most advantageous:

Conveyor speed _____ feet per minute 20
 Angle between carriers 30 and 32 degrees 100
 Angle between carriers 26 and 28 do 100
 Speed of blades on carriers 30 and 32
 feet per minute 90 10
 Speed of blades on tool carrier members
 26 and 28 feet per minute 126

If the speed of the conveyor 200 were changed, all the above figures must necessarily be changed because a new revolution of forces would become necessary. A variation in the materials treated may also require a different adjustment.

Water and/or other loose material on the work pieces is put out from the central portion of each piece toward the edges thereof and such water and/or loose material either drops from the belt at once or is removed by a suitable scraper (not shown) or by gravity during the return run of the belt. The ends of bars 225 are shown in Fig. 1. Such wipers may aid in cleaning the belt as heretofore stated.

With such a machine, a large output of work is possible and various sizes of work pieces may be fully treated with a minimum amount of attention by the operator. In the case of hides or skins, the treatment may be along the "lines of stretch" of the work piece, a form of treatment recognized in the art of leather manufacture as being advantageous and preferable. The tools produce treated areas on the work pieces which areas are in progressive and overlapping relationship, an effect which is conductive to uniformity in results.

Having described my invention, what I claim as new and desire to secure by Letters Patent of the United States is:

1. In a machine for treating sheet material, a movable work supporting means having a single continuous surface, a plurality of sets of tools mounted for simultaneous movement parallel to said surface and along at least four diverging directions from a central area on said surface, means to drive the tool sets in the said directions to treat sheet material supported on said surface, and means for moving the supporting means during the treatment.

2. In a machine for treating sheet material, a supporting means having a single continuous surface, a plurality of tool sets mounted in X formation and each tool set comprising a series of individual tools mounted for outward action in the X formation on sheet material placed on said surface.

3. In a machine for treating sheet material, a supporting means having a single plane surface for supporting a sheet of material to be treated, a plurality of tool sets mounted for outward movement along at least four diverging paths in a plane adjacent and parallel to said surface, means to drive the tool sets in said paths, and means for moving the supporting means relative to the plurality of tool sets.

4. In a machine for treating sheet material, a supporting means having a single continuous surface for supporting a sheet of material to be treated, a plurality of power driven tool sets mounted for outward movement along at least four diverging paths in a plane adjacent and parallel to said surface, the positions of said tool

sets being adjustable in said plane and each tool set comprising a series of individual tools.

5. In a machine for treating sheet material, a work supporting means having a continuous surface, a plurality of sets of tools mounted for movement in X formation in a plane adjacent and parallel to said surface, means to guide the tools in such movement, and means for moving the work supporting means in and away from operative position with respect to the sets of tools.

6. In a machine for treating sheet material, a table for supporting work pieces, a plurality of sets of tools mounted for movement in X formation in a plane adjacent and parallel to said table, means for moving the table in and away from operative position with respect to the tools, and means to maintain work pieces in position with respect to the table against undue shifting because of the action of the tools.

7. In a machine such as set forth in claim 6 in which the means to maintain the work pieces in position comprises a member extending transverse to the table and arranged to bear down upon a work piece supported by said table.

8. In a machine for treating hides comprising a frame, at least four tool sets mounted thereon for simultaneous divergent paths of operation in a first plane, a table lying in a second plane parallel to said first plane to serve as a backing-up member for a hide to be treated, and means for varying the clearance between the two planes to bring such hide into or out from engagement with the tool sets.

9. In a hide treating machine comprising a frame, at least four treating tool carrying members mounted thereon for divergent paths of operation in a first plane upon a work piece such as a hide, four of said tool members adapted to operate tools from a central area of said hide into and along the shank areas, a table lying in a second plane parallel to said first plane to serve as a backing-up member for the hide to be treated, and means for varying the clearance between the two planes to bring the work piece into or out from engagement with the tools.

10. In a hide treating machine, four treating tool carrying members mounted in X formation for divergent operation from a central area of a spread out hide toward the shank areas of said hide, said mounting being in a first plane, additional treating tool carrying members arranged to place the hide under tension along the backbone line during said operation, a table lying in a second plane to serve as a backing-up member for the hide to be treated, and means for varying the clearance between the two planes to bring the hide into or out from engagement with the hide treating tools.

11. In a hide treating machine comprising a frame, four hide treating tool carrying members mounted thereon in X formation for divergent paths of operation in a first plane, a table lying in a second plane parallel to said first plane to serve as a backing-up member for a work piece to be treated by the tools, means for varying the clearance between the two planes to bring such a work piece into or out from engagement with the hide treating tools, and means controlled by the presence of the hide upon the table to lift the table into operative position.

12. In a hide treating machine comprising a frame, four treating tool carrying members mounted thereon in X formation for divergent paths of operation in a first plane, a table lying

in a second plane parallel to said first plane to serve as a backing-up member for a work piece to be treated, means for varying clearance between the two planes to bring such a work piece into or out from engagement with the hide treating tools, and conveying means for moving the hide along the table.

13. In a putting-out machine comprising a frame, a table mounted on said frame, at least four sets of putting-out tools mounted parallel to said table for simultaneous and diverging paths of movement in a horizontal plane, and a conveyor for transferring a work piece such as a hide across the surface of the table, the distance between the horizontal plane of tool movement and the table being variable to bring the work piece into and out from engagement with the putting-out tool sets.

14. In a putting-out machine comprising a frame, a table mounted on said frame, four sets of putting-out tools mounted in X formation and parallel to said table for diverging paths of movement in a horizontal plane, and a conveyor belt for transferring a spread-out piece such as a hide across the surface of the table, the said paths of movement conforming generally with the shank areas of the work piece, and means for varying the distance between the horizontal plane of tool movement and the conveyor belt to bring the work piece into and out from engagement with the putting-out tool sets.

15. In a putting-out machine comprising a frame, a table mounted on said frame, at least four sets of putting-out tools mounted parallel to said table for diverging paths of movement in a horizontal plane and conforming with the shank areas of a spread-out hide to be treated, additional sets of tools mounted in said horizontal plane to maintain the hide under tension along the backbone line during the treating operation, a conveyor for transferring the hide across the surface of the table, and means to bring the table, conveyor and hide into operating position in cooperation with the tool sets.

16. In a putting-out machine comprising a frame, a table mounted on said frame, at least four sets of putting-out tools mounted parallel to said table for simultaneous and diverging paths of movement in a horizontal plane, a conveyor belt for transferring a hide across the surface of the table, and yieldable means to lift the table and conveyor to bring the hide into and out from engagement with the putting-out tool sets.

17. A machine of the type set forth in claim 16, in which said conveyor belt is operable to transfer the hide while said hide is being worked upon by the putting-out tools to produce progressive overlapping treated areas on the hide.

18. A machine of the type set forth in claim 16, including holding means tending to retain the hide in position relative to the conveyor belt while being worked upon by the putting-out tools.

19. In a machine for treating hides, a support forming a backing for a hide, a plurality of tools operating in a common plane for treating a hide on said support, means for lifting the support to press the hide against said tools and for moving the hide along said plane relatively to said tools while maintaining the hide in pressing engagement with said tools, and said tools being arranged in at least four diverging sets thereby to produce progressive overlapping treated areas on the hide.

20. In a machine of the class described, a support for backing a hide, a plurality of tools ar-

ranged in sets diverging in a horizontal plane for operating upon a hide backed by the support, means for moving the support and hide parallel to said horizontal plane, means operating in timed relation to the movement of the hide for effecting relative movement of the support and tools to press the hide between them, and means for moving the tools in outwardly directed paths in said plane while the hide is thus held under pressure thereby to produce progressive overlapping treated areas on the hide.

5 21. A machine of the type described in claim 20 including means tending to retain the hide in position relative to the means for moving the hide to resist any excessive strain placed upon the hide by one or more of the tool sets.

10 22. A machine of the type described in claim 20, in which the sets of tools are adjustable to vary the angles of divergence.

20 23. In a machine for treating hides, a yieldable support for backing a spread-out hide, at least four diverging sets of tools for operating upon the hide backed by the support, means for moving each set of tools during said operating, the said latter means being firmly mounted with the sets of tools on a fixed frame, and means for moving the support into and out of operative relationship with the sets of tools.

25 24. In a machine for treating hides, a support for backing a spread-out hide, four diverging sets of tools, one set arranged to operate outwardly on each flank portion of the hide, two additional sets of tools arranged to pull both ways along the backbone line of the hide, and means for moving the support together with a hide thereon by and in engagement with the tools, said movement being in the same direction as the backbone line.

30 25. In a machine for treating sheet material, in combination, a smooth support for sheet material to be treated, a conveyor belt arranged to carry such sheet material across and over the surface of the smooth support at a uniform rate, tools mounted parallel to the smooth support to operate upon the sheet material when the latter is moved into material treating position, and means motivated by the leading edge of the sheet material to move the sheet material, belt and support into said material treating position when the sheet material has been conveyed into position opposite that of the tools, said means also being operable by the trailing edge of the sheet material to move the sheet material, belt and support away from said material treating position after adequate treatment by the tools.

35 26. In a machine for treating sheet material, a frame, sets of individual tools mounted thereon in X formation, each set being arranged to perform work outwardly in said X formation, a conveyor belt adapted to support pieces of work for successive presentation to the sets of tools, a table over which the conveyor belt is arranged to slide, said table being adapted to serve as a backing-up member during treatment of the work pieces by said tools, means to move the conveyor during the work treating operation, and means operating in timed relation with the position of each work piece relative to the tool sets to lift the table to press the work piece on the moving conveyor against the tools and to lower the table when treatment of each work piece is adequate.

40 27. A machine of the type described in claim 26, in which the means to lift the table is operated by fluid pressure.

DAVID EDGAR.
